CLAIM

The ornamental design for a cane shaped massaging tool, as shown and described.

DESCRIPTION

FIG. 1 is a front view.

FIG. 2 is a left side view.

FIG. 3 is a right side view.

FIG. 4 is a rear view.

FIG. 5 is a top view.

FIG. 6 is a bottom view.

FIG. 7 is a prospective side view; and,

FIG. 8 is a perspective side view.

1 Claim, 8 Drawing Sheets**FIG. 1**

FIG. 2

FIG. 3

FIG. 4

FIG. 5

FIG. 6

FIG. 7

FIG. 8
